6 Claims. (Cl. 272—57)

6 Claims. (c)

This invention refers to a mechanical apparatus for mobilizing joints with reduced mobility, by stretching the soft parts of the joint, such as muscles, capsules and ligaments. Often the ill or damaged joint has no own force of affecting movements, and for this reason it is necessary to use external forces for performing the stretching work.

The chief purpose of this invention is to construct an apparatus for such stretching purposes operated by the movements of any other joint of the patient's limbs, for instance, an undamaged joint near the damaged joint.

Another purpose of this invention is to construct an apparatus for stretching and moving the stiff joints by means of a rotary or oscillatory mass moved by the movements of the patient himself.

Another purpose of this invention is to construct the apparatus in such manner that the movement imparted to the damaged joint is limited to certain angles to which the apparatus may be set, either manually or automatically. This renders it possible for the patient to keep the motion of the damaged joint in the apparatus within the limits of pain of the joint.

Another purpose of this invention is to construct the apparatus in such manner that the patient can alter the setting of the apparatus to other angles, thus rendering it possible for him to successively stretch and mobilize the joint without more pain than he can easily stand.

Other purposes of this invention will be evident from the following specification and the claims.

One embodiment of my invention is illustrated in the annexed drawings.

Fig. 1 shows a side view of a gymnastic apparatus in accordance with this invention.

Fig. 2 shows a top view of the same with some parts broken away. Fig. 2 may be said to be a

(CL. 272—57)
stationary frame having a double seat 2, on which the patient sits when using the apparatus. To this frame brackets 4 are secured, carrying coaxial journals 3, on which a lever 5 is rockably journaled. Another bar 6 extends substantially horizontally. On the lever 5 a shoe or sleeve 8 is slidably arranged which carries a pin 7, by means of which a connecting rod 9 is articulately connected with the lever 5. The rod 9 acts on a crank 110 driving the fly-wheel 10. A screw 11 with a handle serves to clamp the sleeve 8 in any desired position along the lever 5. By setting the sleeve 8 to different positions on the lever 5 it is possible to 15 adjust the angle, through which this lever is rocked, when the fly-wheel 10 rotates.
The lever 5 is integral with (or rigidly connected with) a sleeve 12, which is rockably journaled on the journals 3. Through said sleeve the bar 6 passes and a clamping screw 13 in the sleeve 12 serves to clamp the bar 6 rigidly in the position set in relation to the sleeve 12 and consequently also to the lever 5. The bar 6 also carries a heavy mass or pendulum weight 14 to be 25 clamped by means of the screw 15 in the desired position on said bar. This weight serves to counter-balance the weight of the patient's leg and also the weight of the parts resting on the bar 6. Preferably, the lever 5 extends substantially at 30 right angles to the bar 6.
A bar 16 carries a double foot-rest 17 which may be clamped in any desired position on the bar 16 by means of a clamping screw 18. To this bar also a calf-support 19 is detachably attached 35 which may be set in the desired position by means of a clamping screw 190. The bar 16 is integral with or rigidly secured to a circular disc 20 which is rotatably journaled on the pin or bolt 21. This pin also articulately connects the 40 bar 6 with a bar 22, which extends more or less vertically and is yoke-shaped, as seen in Figs. 3 and 4. At its upper end this bar 22 carries a pin or bolt 23 connecting the same with a bar 24, extending more or less horizontally.
On one leg of the double bar 22 a sleeve 25 is 45 slidable which may be clamped in its position as set by means of a clamping screw 26. In this sleeve a screw or worm 27 is rotatably but not displaceably journaled, and the threads of this screw mesh with corresponding worm wheel threads 28 on the periphery of the disc 20. Thus, when the screw 27 is rotated by turning the wheel 29 on its shaft, the disc 20 and consequently also the bar 16 are rotated correspondingly, that is, the

bar 16 is set to different angular positions in relation to a vertical line (reckoning in the position of rest of said bar). The periphery of the disc 20 carries one or more graduated scales co-operating with a fixed index or the like on the sleeve 25. Thus, it is possible directly to read the angle to which the disc 20 has been set in relation to a vertical line.

A bar 30 extends along the bar 24 and each of those two bars encloses the other by means of sleeves 31, 32 having clamping screws 33, 34. Thus, the sleeve 31 may be permanently secured to (integral with) the bar 30 and be temporarily clamped to the bar 24, while the bar 24 is rigidly secured to the sleeve 32. By adjusting those two sleeves 31, 32 in relation to each other, the length of the combined bar 24, 30 may be adjusted, within the limits concerned. The bar 30 is journalled on a journal 352 in a sleeve 351, which is displaceable along a bar 35 and may be clamped to it by means of a screw 36. The bar 35 is permanently and rigidly fixed on the machine frame 4.

To the bar 6 a thigh holder 37 is detachably secured which may be set to different positions by means of a clamping screw 38. This holder is curved and is adapted to engage the patient's thigh from above.

The apparatus described is used as follows:

The patient sets on the seat 2 to the right or to the left of the bar system in such manner that the damaged leg is next to that bar system. He places the foot of his damaged leg on the foot support 17 and may fix it thereby means of a strap 39 or the like, if desired. The patient's calf then rests on the support 19 engaging the calf from behind, while his thigh is engaged from above by the holder 37. Supposing that the patient's knee joint is damaged and more or less stiff, the patient now turns the wheel 29 until he feels a certain (still tolerable) pain in the damaged joint. By means of the undamaged muscles in his leg he now moves the bar system 22, 24, 30, 6 up and down through an angle. To that bar system the bar 5 is connected, as said bar is clamped to the bar 6. The rocking motion of the parallelogram 22, 24, 6, 30 is also imparted to the bar 5 (while the bar 35 is stationary). The rocking motion of the bar 5 drives the fly-wheel 10 via the crank mechanism 7, 8, 9 and the angle of the rocking motion is determined by the position to which the sleeve 8 has been set on the bar 5. These motions are illustrated in Figs. 6 and 7.

The size of the angle through which the damaged knee joint is moved (stretched) is determined by the setting of the sleeve 8 on the bar 5. As the stretching of the knee joint proceeds, the patient turns the wheel 29 and consequently rocks the disc 20 through the desired angle successively. The number of degrees may be read on the scale on said disc and is annotated. Thus, it is possible for the patient or for the physician to control the stretching and to conduct it in accordance with a fixed scheme.

When it is desired to move the disc 20 through a great angle, to set the bar 16 rapidly, it is possible to loosen the screw 26 and draw the sleeve 25 and the screw 27 out of engagement with the threads 28 on the disc 20. Then the threads 27, 28 are brought into mesh again and the angle may be exactly set by means of the wheel 29.

As is evident from Figs. 6 and 7, the knee joint is somewhere in the neighbourhood of the shaft 21, while the hip joint is in the neighbourhood of

the shaft 3. To set the shaft 21 in the correct position, the bar 6 is set in the sleeve 12. The bar 16 is set to follow the direction of the calf of the patient's stiff leg. The sleeves 8, 351, 31, 32 are also set in such positions that the motion imparted to the sick leg is within the limits of tolerable pain in the joint to be stretched. During the stretching operation the wheel 29 is turned to increase or decrease the angle α , so that said limits are slowly exceeded and the soft parts of the joints are successively stretched.

It is evident that the maximum variation of the angle α during the oscillating motion of the bar system may be set also by adjusting the length of the double bar 24, 30 and by setting the sleeve 351 at different levels on the bar 35.

In some cases a pendulum may be used in combination with or instead of the fly-wheel 10. Such pendulum may be placed on the bar 5 (or on a corresponding bar in other embodiments), and then two settable stoppers are preferably provided to limit the pendulum motion of the bar.

The apparatus as shown is in the first line intended particularly for the mobilization of knee joints. But it is evident that the apparatus in accordance with this invention may be adapted to mobilize other joints of the body. Just as the knee joint is mobilized by means of the motion of the hip joint in the embodiment shown, the elbow joint may be mobilized by the action of the shoulder joint, etc. In analogous manner the wrist and foot joints may be mobilized.

What I claim is:

1. A gymnastic apparatus for mobilizing joints, comprising, in combination, a frame, a stationary shaft in said frame, a system of articulately connected levers rockable on said shaft, a fly-mass connected with said system of levers, a bar articulately connected with said system of levers, holders on said bar for one part of the body at the joint to be mobilized, the part of the patient's body on the other side of said joint being placed along said system of levers, and a setting mechanism for setting the angle between said bar and said system of levers and thus for controlling the relative motion between them.

2. A gymnastic apparatus for mobilizing joints, comprising, in combination, a frame, a stationary shaft in said frame, a lever fulcrumed intermediate of its ends on said shaft, a bar articulately connected with said lever, means for holding those parts of the patient's body which are on either side of the joint, substantially along said lever and said bar, respectively, a device for setting the angle between said lever and said bar, means including a polygon of rods for rocking said bar, when said lever is rocked, and a counterweight connected with said lever.

3. A gymnastic apparatus for mobilizing joints, comprising, in combination, a frame, a shaft journalled in said frame, a lever fulcrumed on said shaft, a bar articulately connected with said lever, means for holding the parts of the patient's body on both sides of the damaged joint substantially along said lever and said bar, respectively, a second bar connected with said first bar and movable together with the same, a third bar articulately connected with said second bar, a stationary bar, and an articulated joint between said third bar and said stationary bar.

4. A gymnastic apparatus for mobilizing joints, comprising, in combination, a frame, a shaft journalled in said frame, a lever fulcrumed on said shaft, a first bar articulately connected with said lever, means for holding the parts of the pa-

tient's body on both sides of the damaged joint substantially along said lever and said bar, respectively, a second bar, a worm gear between said first and second bars, a third bar articulately connected with said second bar, a stationary bar, and an articulated joint between said third bar and said stationary bar.

5. A gymnastic apparatus for mobilizing joints, comprising, in combination, a frame, a shaft journalled in said frame, a lever fulcrumed on said shaft, a first bar articulately connected with said lever, means for holding the parts of the patient's body on both sides of the damaged joint substantially along said lever and said bar, respectively, a second bar, a worm gear between said first and second bars, a carriage for said worm gear settable along said second bar, a third bar articulately connected with said second bar,

a stationary bar, and an articulated joint, between said third bar and said stationary bar.

6. A gymnastic apparatus for mobilizing joints, comprising in combination, a frame, a shaft journalled in said frame, a lever fulcrumed on said shaft, a bar articulately connected with said lever, means for holding the parts of the patient's body on both sides of the damaged joint substantially along said lever and said bar respectively, a second bar connected with said first bar and movable together with the same, a third bar articulately connected with said second bar, a stationary bar, an articulated joint on said third bar near its end, and a clamp on said third bar between its end and said articulated joint, said clamp being settable to different positions on said stationary bar.

GUSTAF RICHARD ZANDER.
